UNITED STATES PATENT OFFICE.

SAMUEL BROWN, OF NEW YORK, N. Y.

TRAVELING CASE, SAMPLE CASE, OR THE LIKE.

Application filed April 6, 1926. Serial No. 100,081.

The present invention relates to sample boxes, traveling bags, trunks or other cases, and has for its object to provide the same with means for holding an exchangeable sign such as a label or card containing the name and address of the addressee or that of the sender or the like.

Particularly with cases such as sample boxes which are designed for repeated use through the mail it has hitherto been necessary for every other sender to remove the label of the previous sender and paste on a new label or strike or scratch out the former address and write or print the new address. This not only consumes time but after a short while the appearance of the case is spoiled and the latter has to be discarded.

According to my invention I provide the box with an inwardly yielding pocket or holder for a card, label or other sign to be exposed through an opening in the box which pocket or holder is not accessible from the outside but which on the opening of the case will permit in a very convenient and quick manner the exchange of the cards or labels.

I also provide suitable means whereby the pocket or holder will be secured in position for use and prevent the slipping out or loss of the sign.

In the present example I have shown my invention applied to a box shaped cardboard carton or case. It is, however, clear that the same may be used for similar purposes on cases of any other shape and material.

One embodiment of my invention is illustrated in the accompanying drawing which forms part of this specification and in which similar reference characters denote corresponding parts:—

Fig. 1 is a perspective view of a square cardboard case equipped with my device;

Fig. 2 is a section on the line 2—2 of Fig. 1;

Fig. 3 is a section on the line 3—3 of Fig. 1; and

Fig. 4 is a bottom view of my device.

In the drawing a denotes a square case such as is usually employed as a sample box and which consists of a lower box shaped section a^1 forming the container proper and a box shaped upper section a^2 serving as cover. This cover is provided with a substantially U-shaped incision a^3 to form a flap a^4 which is provided with a rectangular recess a^5 . Covering the rear of said flap and adapted

to be fixed along its upper longitudinal edge or on a line parallel to the foldable edge of the flap a^4 by rivets d or the like to the inner face of the cover a^2 is a second flap b which may be of similar material as that of the case. The latter in width and breadth is somewhat larger than the flap a^4 so that it overlaps the edges of the flap a^4 . The sides of the latter are fixed along their marginal edges to the second flap b by rivets c or the like, so that the two flaps thus joined can together swing inwardly and will form a sheath or pocket for the reception of an exchangeable label, card or other signs s . The unattached longitudinal edge of the second flap b may be provided centrally with a finger piece or tab b^1 and is adapted to be detachably fastened to the inner face of the cover by suitable separable means such as snap fasteners e , e^1 , whereby the sheath or pocket will be secured in position of use and hold the card s tightly preventing its accidental displacement in or slipping out from said pocket.

For ornamental purposes and to lend the box a neater appearance and also for the purpose of reinforcement of the pocket when the box is made of cardboard or the like, the outer face of the flap a^4 has attached to it around its margins by means of rivets f^1 a metal frame f . Covering the recess a^5 of the flap a^4 is a transparent shield m of mica or the like.

It will be seen that when the cover a^2 is slipped over the section a^1 and as usual is strapped or tied to it the card or label s is not accessible from the outside of the case. The exchange of one label for another is comparatively easy, it being only necessary after opening the case to unfasten the snap fasteners e , e^1 , and bend the pocket inwardly, or rearwardly so as to conveniently reach the card.

Since various changes can be made in the construction of my device without departing from the principle of my invention I do not wish to limit myself to the details described or shown except as defined in the claims.

What I claim is:—

1. In a mailing or traveling case having an opening for the exposure of a sign, a sign holder including an inwardly yielding section at the rear of said opening forming an integral part of said case and means for locking said yielding section in operative

position to secure the sign in said sign holder.

2. In a mailing or traveling case having an opening for the exposure of a sign, an inwardly yielding sign holder arranged inside said case and composed of two interconnected sections of which one is an integral part of said case and means for holding said sign holder rigidly in position of use and thereby secure the sign therein.

3. In a mailing or traveling case having an inwardly yielding sign holder arranged

inside said case and composed of two interconnected sections of which one is an integral part of said case and the second is fixed to said case at one of its longitudinal edges and means for separably fastening the opposite longitudinal edge of said second section to said case for holding said sign holder rigidly in position of use and thereby secure the sign therein. 15 20

In testimony whereof I affix my signature.

SAMUEL BROWN.
